Filed Aug. 5, 1966, Ser. No. 3,359

Term of patent 14 years

(Cl. D56—4)

The single figure is a left side, top and front perspective view of a radio cabinet or similar article, showing my new design.

The two loudspeaker grille cloths each shaped like a four-sided truncated pyramid at each end of the front surface of the cabinet are continuous within the boundaries shown. The dominant features of my new design are shown in solid lines in the drawing.

I claim:

The ornamental design for a radio cabinet or similar article, as shown and described.
